Primary Examiner—Joel Sincavage(74) *Attorney, Agent, or Firm*—Fish & Richardson P.C.(57) **CLAIM**

The ornamental design for a battery, as shown and described.

DESCRIPTION

FIG. 1 is a perspective view of the battery design of the invention;
 FIG. 2 is a top view of the battery of FIG. 1;
 FIG. 3 is a bottom view of the battery of FIG. 1;
 FIG. 4 is a side view of the battery of FIG. 1;
 FIG. 5 is another side view of the battery of FIG. 1; and,
 FIG. 6 is a cross-sectional view of the battery of FIG. 5,
 taken along line 6—6.
